128 Michael Gibney
No. 128 Design for Spoons
Patented June 19th 1847.

Des. 128

Michael Gibney, New York, New York
Letters Patent Design No. 128, dated 19th June 1847.

The schedule referred to in these Letters Patent are making part of the same

To all whom it may concern: Be it known that I Michael Gibney of the City County and State of New York, have invented an improved pattern for Silver and other metallic spoon handles, Forks, and articles for Table use, and I do hereby declare that the following is a full and exact description of the same reference being had to the annexed drawings which make a part of this specification.

The head of the handle is elliptical, and the shank is curved, both ornamented in the style of Louis 14th as portrayed in the annexed drawing.

Fig 1. represents the back, and Fig 2, the front side of a spoon with the configuration and embellishments which form my improvement.

What I claim as my invention and desire to secure by Letters Patent is the configuration and ornaments to be applied to silver and other metallic spoons, Forks and articles of Tableuse, as herein delineated
